UNITED STATES PATENT OFFICE

121,560

DESIGN FOR A DRAWER PULL OR SIMILAR ARTICLE

Earl Borchers, Rockford, Ill., assignor to American Cabinet Hardware Corp., Rockford, Ill., a corporation of Illinois

Application May 11, 1940, Serial No. 92,298

Term of patent 7 years

To all whom it may concern:

Be it known that I, Earl Borchers, a citizen of the United States, residing at Rockford, in the county of Winnebago and State of Illinois, have invented a new, original, and ornamental Design for a Drawer Pull or Similar Article, of which the following is a specification, reference being had to the accompanying drawing, forming a part thereof.

Figure 1 is a perspective view of a drawer pull or similar article showing my new design.

Figs. 2 and 3 are side and front views respectively of the same.

I claim:

The ornamental design for a drawer pull or similar article, substantially as shown.

EARL BORCHERS.
